UNITED STATES PATENT OFFICE

2,423,797

HIGH-FREQUENCY CIRCUIT

Grote Reber, Wheaton, Ill., assignor to Stewart-Warner Corporation, Chicago, Ill., a corporation of Virginia

Application January 1, 1944, Serial No. 516,737

7 Claims. (Cl. 178—44)

1

My invention relates generally to quasi-optical and ultra high frequency circuits, and more particularly to radio frequency choke assemblies.

It is an object of my invention to provide an improved radio frequency choke which is completely contained in the tuned circuit of a transformer.

A further object is to provide an improved ultra high radio frequency transformer having two coupling impedances in parallel so that both the plate and grid choke lines may be brought out separately without interaction between them, and that they may be made of optimum length.

A further object is to provide an improved radio frequency choke for ultra high frequency circuits which incorporates blocking and by-pass condensers which are advantageously located with respect to their necessary size.

A further object is to provide an improved ultra high frequency circuit structure usable as part of a wide band amplifier which has high gain and small losses.

Other objects will appear from the following description, reference being had to the accompanying drawings, in which

Fig. 1 is a central longitudinal sectional view of the improved assembly, and

Fig. 2 is a schematic wiring diagram showing the lumped constant electrical circuit equivalent of the assembly shown in Fig. 1.

The circuit structure comprises an inner cross-T 10 having coaxial conductors 12 and 14 held therein by insulating spacers 16. One end of the conductor 12 is connected to a plate clip 18 while its other end is connected to a plate 20 forming part of a by-pass condenser C3. The conductor 14 is similarly connected between a grid clip 22 and a plate 24, the latter forming part of a by-pass condenser C4.

Concentric with and surrounding the left leg 10a of the T structure 10 is a plate line tube 26, while a grid line tube 28 surrounds and is concentric with the right hand leg 10b of the cross-T 10. The tubes 26 and 28 are joined to tubular coupling stubs 30 and 32 which are concentric with and surround portions of the upper leg 10c and lower leg 10d, respectively. The stubs 30 and 32 are joined to the legs 10c and 10d, respectively, by their end walls 33.

The plate clip 18 is separated from the leg 10a by a dielectric tube 36 thus forming a plate blocking condenser C1. Similarly, the grid clip 22 is separated from the leg 10b by a dielectric tube 37 to form a grid blocking condenser C2.

In the equivalent lumped constant circuit dia-

2

gram of Fig. 2, Cp and Lp represent the output capacity and plate lead inductance within the first tube of an amplifier of which the structure of Fig. 1 forms the interstage coupling mesh. Cg and Lg similarly represent the input capacity and grid lead inductance within the second tube of the amplifier.

When the structure of Fig. 1 is thus used as the coupling between two stages of an amplifier the +B potential source is connected to the plate 20 of condenser C3 while the grid bias negative voltage source is connected to the plate 24 forming part of condenser C4.

The inductance L1 determines the plate tuned frequency and represents the impedance of plate line tube 26 and the leg 10a. Inductance L3 determines the grid tuned frequency and represents the impedance of the grid line tube 28 and the leg 10b. The parallel inductances L2 determine

the grid to plate coupling, and thus the band width, and represent the impedances of the coupling stubs 30 and 32 with reference to the portions of legs 10c and 10d which they respectively surround.

25 The inductance L4 is the plate radio frequency choke and represents the impedance of the coaxial line comprising conductor 12 and legs 10a and 10d. Similarly, the inductance L5 constitutes the grid radio frequency choke and represents the impedance of the coaxial line comprising conductor 14 and the legs 10b and 10c.

Those portions of the legs 10c and 10d which extend beyond the coupling stubs 30 and 32 are preferably made of such length that the lengths 35 of the coaxial lines provided by conductors 12 and 14 (L4 and L5) are each one-quarter wavelength at the midband frequency f_0 . The inductive reactance of plate choke is

$$40 \quad X_4 = Z_4 \tan \frac{\omega l}{v}$$

where Z_4 is characteristic impedance of concentric conductors 12 and 10a, 10d (L4 in equivalent lumped circuit). At midband frequency f_0 , X_4 will be infinite since

$$\frac{\omega l}{v} = \lambda/2.$$

In the foregoing, ω is the angular velocity in radians per second, l is the length of the line in centimeters, λ is the wave length in centimeters, while v is the velocity of radiant energy propagation, namely, 3×10^{10} centimeters per second.

At the edges f_1 and f_2 of the frequency band the choke impedance X_4 will be

$$Z_4 \tan \left(\frac{\pi f_1}{2f_0} \right)$$

and

$$Z_4 \tan \left(\frac{\pi f_2}{2f_0} \right)$$

The impedance of the grid radio frequency choke comprising conductors 14 and 10b, 10c (L5 in equivalent lumped circuit) at the frequencies at the edge of the band may be computed by similar formulas.

The characteristic impedance of the choke conductors 12 and 10b, 10d may be of a value in the order of 200 ohms and thus several thousand ohms of choke reactance may be developed in a circuit having tuned impedances of only a few hundred ohms. The condenser C3 has a reactance of only a few ohms, thus the amount of radio frequency energy which can enter the +B and negative grid voltage supply leads is negligible.

Since the choking reactance of L4 and L5 is very high, the internal blocking condensers C1 and C2 may be made small, which is advantageous in the circuit and makes the physical structure of these condensers very simple. On the other hand, the main by-pass condensers C3 and C4 are external of the structure, and, hence, may be conveniently made relatively large so as to have the desired very low reactance.

The structure illustrated is designed for use in an amplifier for a wide frequency band, such as a 10 megacycle band, in a frequency range from 100 to 1,000 megacycles. Within this range the structure has been found to provide high gain and affords very effective chokes to prevent the radio frequency from entering the potential supply circuits.

As above pointed out, the lengths of the choke extensions may be varied to make L4 and L5 exactly one-quarter wave length long, this being illustrated in Fig. 1 by the fact that the leg 10c is longer than the leg 10d, and, correspondingly, the grid line tube 28 is shorter than the plate line tube 26.

It will be understood by those skilled in the art that other variations in the details of the structure may be made without departing from the underlying principles of the invention. I, therefore, desire, by the following claims, to include within the scope of my invention all such modifications and variations whereby substantially the results of my invention are obtained by substantially the same or equivalent means.

I claim:

1. An interstage coupling for an ultra high radio frequency amplifier comprising, a tubular cross-T, a pair of conductors respectively extending coaxially through adjacent legs of said cross-T, capacitative connections between each end of each of said conductors and its adjacent end portion of said cross-T, said capacitative connections comprising blocking and by-pass condensers, and tubular plate and grid line elements completely surrounding oppositely directed legs of said cross-T and partially surrounding the intermediate legs thereof, said tubular plate and grid line elements being interconnected and connected to said intermediate legs of said cross-T, the exposed portions of said intermediate legs forming high impedance radio frequency chokes, the effective lengths of said conductors being substantially

of one-quarter wave length at the mid-band frequency to be amplified.

2. An ultra high frequency circuit structure comprising a tubular cross-T, a pair of coaxial conductors each extending through a different pair of adjacent legs of said cross-T, a condenser formed between each end of each of said conductors and the adjacent end portion of its surrounding cross-T leg, and coupling lines in the form of a coaxial tubular member surrounding opposite legs of said cross-T and surrounding portions only of the intermediate cross-T legs, whereby the portions of said intermediate cross-T legs which are not surrounded by said coupling lines form radio frequency choke extensions.

3. A circuit structure for use in interstage coupling of an ultra high frequency amplifier comprising, a cross-T, a pair of conductors each extending coaxially through a pair of adjacent arms of said cross-T, a tubular grid line and tubular plate line respectively surrounding oppositely directed legs of said cross-T, coupling stubs surrounding portions of the intermediate legs of said cross-T's and connected to said tubular grid and plate lines, a blocking condenser formed by a cap surrounding and insulated from the end of one of said opposed legs of said cross-T, a similar blocking condenser at the outer end of the other of said opposed legs of said cross-T, and by-pass condensers formed at the ends of the intermediate legs of said cross-T, said by-pass condensers each having one plate thereof formed by a portion of the intermediate cross-T leg.

4. An ultra high frequency circuit structure for coupling the output of a first electron discharge device with the input of a second electron discharge device, said devices forming parts of an amplifier, the combination of a cross-T, a first coaxial conductor extending through adjacent legs of said cross-T, a second coaxial conductor extending through the other two legs of said cross-T, caps secured to the ends of opposed legs of said cross-T, said caps being insulated from the adjacent end portions of said cross-T legs to form blocking condensers, the blocking condenser at the end of said first conductor being adapted to be connected to the output of said first electron discharge device and the blocking condenser connected to the second conductor being adapted to be connected to the input of said second electron discharge device, by-pass condensers connected respectively to the other ends of said conductors respectively, each of said by-pass condensers comprising a radially-extending flange at the adjacent end of the surrounding cross-T leg and a plate spaced and insulated from said flange, said plates of said by-pass condensers being adapted to be connected respectively to the positive plate voltage source and to the negative grid voltage source, and interconnected tubes surrounding the legs of said cross-T, except for portions of substantial length adjacent said by-pass condensers, said portions being of such length that the effective length of each of said conductors will be substantially one-quarter wave length at the mid-band frequency, whereby said portions will form high impedance chokes at the mid-band frequency.

5. An interstage coupling for an ultra high radio frequency amplifier comprising, a branched tubular member, a pair of conductors respectively extending coaxially through adjacent legs of said member, connections between each end of each of said conductors and its adjacent end portion of said cross-T, and tubular plate and grid line

elements completely surrounding two legs of said member and partially surrounding the intermediate legs thereof, said tubular plate and grid line elements being interconnected and connected to said intermediate legs of said member, the exposed portions of said intermediate legs forming high impedance radio frequency chokes, the effective lengths of said conductors being substantially of one-quarter wave length at the mid-band frequency to be amplified.

6. An ultra high frequency circuit structure comprising a multi-leg tubular member, a pair of conductors each extending through a pair of adjacent legs of said member, a condenser formed between each end of each of said conductors and the adjacent end portion of its surrounding leg, and coupling lines in the form of a tubular part surrounding two legs of said member and surrounding a portion only of an intermediate leg, whereby the portion of said intermediate leg 20 which is not surrounded by said coupling lines forms a radio frequency choke extension.

7. A circuit structure for use in interstage coupling of an ultra high frequency amplifier comprising, a multi-leg tubular member, a pair of conductors each extending through a pair of adjacent legs of said member, a tubular grid line and a tubular plate line respectively surrounding a pair of legs of said member, a coupling stub surrounding a portion of another leg of said member and connected to said tubular 10 grid and plate lines, a blocking condenser formed by a cap surrounding and insulated from the end of one of said pair of legs of said member, a similar blocking condenser at the outer end of the other of said pair of legs of said member, 15 and a by-pass condenser formed at the end of another leg of said member, said by-pass condenser having one plate thereof formed by a portion of the leg.

GROTE REBER.
